(57) **CLAIM**

The ornamental design for the portion of a ceiling fan housing, as shown and described.

DESCRIPTION

FIG. 1 is a perspective view from below of a portion of a ceiling fan housing in accordance with my design;

FIG. 2 is an enlarged perspective view from below of the portion of a ceiling fan housing in accordance with my design;

FIG. 3 is a top plan view of the portion of a ceiling fan housing in accordance with my design; and,

FIG. 4 is an enlarged representative side elevation view of the portion of a ceiling fan housing in accordance with my design.

The broken lines showing environmental structure are for illustrative purposes and form no part of the claimed design.
